TRIGGER CIRCUIT OF THE MAGNETIC OR
DIELECTRIC TYPE

Simon Duinker, Eindhoven, Netherlands, assignor to
Hartford National Bank and Trust Company, Hartford, Conn., as trustee

Application July 23, 1953, Serial No. 369,793

Claims priority, application Netherlands August 7, 1952

17 Claims. (Cl. 307—88)

The invention relates to trigger circuits of the magnetic or dielectric type which include a variable reactance comprising a medium which is operated in a non-linear part of its polarization characteristic curve and having supplied to it signal oscillations, preferably pulsatory oscillations, and also a supply oscillation the frequency of which is high as compared with the repetition frequency of the signal oscillations, and in which the effective value of the oscillation across the reactance which is set up under the action of the supply oscillation can be increased to a comparatively high value by signal oscillations of definite polarity and be reduced to a comparatively low value by signal oscillations of opposite polarity.

In a known trigger circuit of the magnetic type in which the variable reactance is constituted by a coil the core of which is made of non-linear ferromagnetic material the output current is rectified and then fed back to the input circuit. If the feed-back is properly adjusted two discrete stable conditions separated by a region of unstable conditions are found in the relationship between output alternating current voltage and input direct current. Pulses of suitable value and direction in the input circuit cause the circuit arrangement to pass from one stable condition to the other and vice versa, a large effective value of the output oscillation being set up in one stable condition, a small one in the other stable condition. Some important disadvantages attach to such circuit arrangements, since generally a Graetz arrangement is used to rectify the output current and this requires the use of four rectifier cells.

The ohmic resistance of the Graetz arrangement is connected in series with the supply generator and the coil operating as a variable reactance, resulting in an undue linearizing effect on the required non-linear properties of the circuit.

In addition, the output power is largely dissipated in the rectifier resistor which acts as the only load, so that little power is left for the control of any subsequent trigger circuit connected in cascade with the first one.

The invention obviates these disadvantages and is characterized in that the variable reactance is coupled to a second reactance of opposite polarity, the characteristic curve of which shows the effective value of the oscillation set up across each of the reactances as a function of the polarization comprising at least one unstable region, the said polarization being varied by the signal oscillations so as to exceed this region.

The invention will now be described with reference to the accompanying diagrammatic drawings, in which

Fig. 1 shows a diagrammatic embodiment of a circuit according to the invention of the magnetic type;

Fig. 2 shows a series of curves associated with such a circuit;

Fig. 3 is a curve illustrating the operation of a device according to the invention;

Figs. 4, 5 and 6 show diagrammatically embodiments

of circuits according to the invention of the magnetic type;

Figs. 7 and 8 show diagrammatically embodiments of circuits according to the invention of the dielectric type;

Fig. 9 is a curve illustrating one aspect of the operation of a device according to the invention;

Fig. 10 shows a circuit according to the invention of the magnetic type in which feed-back is provided;

Fig. 11 is a curve illustrating the operation of the circuit shown in Fig. 10;

Fig. 12 is a curve as obtained completely in such an arrangement;

Fig. 13 is a curve illustrating one aspect of the operation of a device according to the invention;

Fig. 14 shows a circuit according to the invention of the dielectric type in which feed-back is provided;

Fig. 15 shows by way of example an embodiment of a push-pull circuit of the magnetic type in which feed-back is provided;

Fig. 16 shows by way of example a similar circuit of the dielectric type, and

Fig. 17 is a characteristic curve as may be obtained in a specific use of circuits according to the invention.

Referring now to Fig. 1, K designates a ferromagnetic core the polarization curve of which, that is to say the curve showing the relationship between the magnetic induction B and the magnetic field strength H , has a non-linear variation. L and W are windings arranged on said core, C is a capacitor which may be linear, G is a supply generator and R a resistor which is assumed to include the losses of the circuit such as the resistance of the supply generator G and of the coil L.

If for example the effective value V_{eff} of the peak value of the alternating current voltage across one of the elements L, C, R or W which is set up under the action of the supply voltage E having a frequency f is considered as a function of the polarization which is rendered effective for example by means of a direct current I which is passed by W, the relationship between these quantities is found to be as shown in the series of curves shown in Fig. 2, subject to some conditions with regard to E, C and f , and this will be set out more fully hereinafter.

In the curve family shown in Fig. 2 the resistor R is taken as a parameter, R increasing with increasing ordinal number.

Let this resistor be small enough for curve 1 to represent the above mentioned relationship. Without adjustment polarization, that is to say at $I=0$, V_{eff} for example across the coil L is equal to V_1 after the supply voltage E is brought into the circuit. On introduction of the adjustment polarization, V_{eff} initially increases continuously with increasing I . On reaching point A of curve 1 V_{eff} leaps discontinuously from the value associated with A to V_2 at point A' along the broken line in the figure. On further increase of I , V_{eff} at least approximately retains this value V_2 , falls off ultimately to the value associated with point B and then falls to value V_3 at point B', as indicated in the figure by the broken line BB'. V_{eff} approximately conserves this value V_3 with further increase of I .

V_{eff} remains at this value on subsequent reduction of I , is ultimately increased to the value associated with point C and thence leaps along the broken line CC' to the value V_2 at point C', which value is maintained with decreasing I . The curve is symmetrical with respect to the V_{eff} axis. The broken lines indicate unstable conditions the variation of which may be ascertained theoretically. The stable region in the proximity of the point $I=0$, $V_{eff}=V_1$ is only re-accessible by switching off and subsequent switching on of the supply voltage E.

When the resistor R is reduced a curved is produced which has substantially the same variation as curve 1

but when R is increased, this variation is modified. Increasing R in a manner such that the curve 2 shown in Fig. 2 is obtained results in a discontinuous leap from a high voltage level to a low voltage level even at a smaller value of I . On further increase of R this unstable region disappears altogether at the lower value of I , as may be seen from the variation of curve 3 shown in Fig. 2. When R is further increased it ultimately has so strong a linearizing effect that discontinuities do not occur either at a low value or at a high value of I . The relationship between V_{eff} and I in this event is indicated by curve 4 shown in Fig. 2.

If the V_{eff} — I curves across one of the other elements, that is to say C , R or W are considered, these curves are found to exhibit a similar form, the numerical values of V_{eff} , however, being different with each element.

As has been stated hereinbefore, not only the B — H curve of the ferromagnetic core, but also the values of the capacity C , of the voltage E and the frequency f affect the value of V_{eff} as a function of I , although the character of the curves is maintained within certain limits. However, the said quantities also affect these curves qualitatively. Thus, the instabilities are enabled to occur only if the product of the capacity C and the square of the frequency f satisfies the condition:

$$\frac{1}{L_{max}} < 4\pi^2 f^2 C < \frac{1}{L_{min}}$$

where L_{min} designates the minimum value of the inductance of L , which occurs at a very high value of adjustment polarization, and L_{max} the maximum value of the inductance of L , which occurs at a very low value of adjustment polarization.

The value of the supply voltage E is also influential. Reduction of E causes the curve 1 to change to curves such as 2, 3 and 4.

If, in the case of the V_{eff} — I curve being formed in the shape of curve 1, the polarization is adjusted to $I=I_0$, as shown in Fig. 3, the value of V_{eff} is either V_2 or V_3 . Assuming this value to be V_2 , a current pulse applied to the winding W equal to or exceeding ΔI_1 and having the same polarity as I_0 will cause V_{eff} to pass from the value V_2 to V_3 .

Any subsequent similar pulse will not have the effect of changing the condition so that V_{eff} will retain its value V_3 at least approximately. However, if an impulse exceeding or equaling ΔI_2 and having a polarity opposite to I_0 follows, it will cause V_{eff} to change from V_3 to V_2 . Also in this case another similar pulse will not cause V_{eff} to change from V_2 to V_3 .

Thus, a train of pulses having alternately opposite polarity and the absolute value of which is at least equal to ΔI_1 or ΔI_2 respectively (it being naturally possible for I_0 to be such that $\Delta I_1=\Delta I_2$) will cause V_{eff} to pass from the value V_2 to the value V_3 and vice versa in the same rhythm, so long as the period of time between the successive pulses is sufficiently large to prevent any effect of the inertia attendant on the changes from one stable condition to the other. As will be shown below, this inertia may be used with advantage.

To obtain the above described effect use may be made of a characteristic curve as shown by curves 2 and 3, there being, in addition, in the case of curve 2 the choice between two unstable regions. So long as other considerations are not significant the region obtained with larger adjustment polarization is to be preferred, since in this event the saturation region of the B — H curve is operated upon, so that the hysteresis losses are kept small, which may be of great value at high repetition frequencies.

If two unstable regions are available, the pulses should not be large enough to cover both regions.

The output signal of the trigger circuit shown in Fig. 1, that is an alternating current voltage having a large or small amplitude according to whether the circuit is in

one stable condition or in the other, may in principle be taken not only from any of the elements L , W , C and R but also from windings which magnetically are connected in parallel with L or W , that is to say, from windings supported from the core in a manner such that their turns embrace the same flux as the turns of L or W . Since the non-linearity of the circuit decreases with increase of R , resulting in less favourable characteristic curves such as curves 3 and 4 shown in Fig. 2, R will generally be kept to a minimum. In this case the output signal taken from R becomes comparatively small so that instead of being taken from R this signal is preferably taken from L or C . In addition, it is found both experimentally and theoretically, that when the output voltage is taken from the windings L and W , or from tap on these windings or from windings connected magnetically in parallel therewith, the ratio

$$\frac{V_2}{V_3}$$

is materially higher and hence is more favourable for many purposes than when the output voltage is taken from the capacitor C or from a resistor included in the circuit. In addition, with tap on L and W or with windings connected magnetically in parallel with L and W , proper proportioning of the number of turns permits stepping up or down the output voltage.

The output voltage of the circuit may be detected by means of an amplitude detector and, if required, subsequently differentiated and so forth, according to the use to which it is to be put.

Hitherto adjustment polarization has been referred to, that is to say, a constant premagnetization of the ferromagnetic core which is effected with the aid of the direct current I_0 which passes through the signal winding W . Naturally, as an alternative said premagnetization may be produced by means of a direct current passing through a winding connected magnetically in parallel with W or by means of a permanent magnet.

In addition, signal pulses have been continually referred to. It will be understood that any oscillation which is positive in relation to I_0 and the amplitude of which exceeds ΔI_1 for a period of time is capable, when superposed on I_0 , of bringing about a change from V_2 to V_3 and that any oscillation which is negative in relation to I_0 and the amplitude of which exceeds ΔI_2 for a period of time is capable, when superposed on I_0 , of bringing about a change from V_3 to V_2 . Pulses, which term is to be understood to mean oscillations having steep flanks, have the advantage that curvatures in the V_{eff} — I_0 curve, for example adjacent the points B and C of the curve 1 shown in Fig. 2, are traversed more rapidly, and hence that the transitions in the output voltage from V_2 to V_3 and vice versa are faster.

In addition, it should be noted that somewhat similar instabilities are produced in a circuit of the kind shown in Fig. 1 as a function of the supply voltage E at a constant adjustment polarization. This form of instabilities has a limitation in that, if they are required to be used for a trigger effect, the supply voltage must be modulated by the signal oscillations to which the circuit is required to respond.

In a circuit arrangement as shown in Fig. 1 the supply oscillation produces fluxes in the ferromagnetic core which not only feed the required voltages into the coil L but also feed undesired voltages into the winding W and any windings connected magnetically in parallel therewith. These voltages become unduly high in the case of high internal impedance of the direct current supply and the signal supply, and in the case of low internal impedance may produce in the said windings appreciable short-circuit currents which have an undue retarding effect on the required sudden changes. The said short-circuit currents may be balanced out by connecting chokes in series with the windings, but in this case the

signal oscillations, particularly at a high repetition frequency thereof, are appreciably attenuated and also slightly retarded, while at the same time excessive voltages are apt to be set up.

These high voltages or powerful currents may be largely balanced out by preventing at least components at the frequency f and odd multiples thereof from being set up at the input end of the circuit arrangement. This may be ensured in a number of ways known per se with magnetic modulators, for example by the use of two push-pull connected devices in accordance with the invention one set of windings of which is connected in series and the other set in series opposition, as shown in Fig. 4, or by using a three-legged core having supply windings wound on its outer legs so as to produce an annular magnetic field for these legs (see Fig. 5), the centre leg having produced in it only fluxes the frequencies of which are even multiples of the supply frequency.

Instead of a supply generator having an impedance comprising a preferably minimum ohmic component being connected in series with a non-linear inductance and a capacity it may be connected in parallel with a non-linear inductance and a capacity, as shown in Fig. 6, which results in a curve family similar to the one produced by the series connection except that now linearization is increased as the parallel impedance is decreased. Hence in this event use will preferably be made of a supply generator having a very high internal impedance. Similar considerations apply to the circuit arrangements shown in Figs. 4 and 5. It should be noted that an impedance connected in series with the parallel combination of L and C , as shown by broken lines in Fig. 6, results in an additional degree of liberty with which for example $\Delta I_1 + \Delta I_2$, that is the minimum pulse height allowing the change from one stable condition to the other, can be controlled. As an alternative this may be done by increasing or decreasing the capacitor C within the fixed limits but, in the case of a large value of C this requires comparatively large adjustment polarizations and this is not the case with control by means of Z .

Even a series circuit as shown in Figs. 1, 4 and 5 may otherwise have an additional degree of liberty introduced in it in that an impedance is connected in parallel with the supply generator G .

Hitherto we have restricted our discussion to the case in which the medium which is operated in a non-linear part of its polarization characteristic curve is ferromagnetic. However, it is also possible for the medium to be of dielectric nature.

In Fig. 7, M designates a dielectric material the polarization characteristic curve of which, that is the curve showing the relationship between the dielectric displacement D and the electric field strength F , is non-linear, C designates a capacitor containing this material, L an inductance which may be linear, G a supply generator and R a resistor which is considered to include the resistance of the supply generator G , the coil L , and so forth.

If for example the effective value V_{eff} of the alternating current voltage set up across one of the elements L , C or R under the action of the supply voltage E at a frequency f is considered as a function of the polarization which is set up by means of a direct current voltage V applied across C , a relationship is found to exist between V_{eff} and V which is similar to the relationship between V_{eff} and I in the circuit arrangement shown in Fig. 1.

Here again quantities such as L , E and f act upon the value of V_{eff} as a function of V , and also qualitatively upon the variation of the curves. In this case it is possible for instabilities to be produced, only if the condition

$$\frac{1}{C_{max}} < 4\pi^2 f^2 L < \frac{1}{C_{min}}$$

is satisfied, where C_{min} represents the minimum value

of the capacity of C set up at a very low value of adjustment polarization and C_{max} the maximum value of the capacity of C resulting at a very high value of adjustment polarization.

Thus, a proper choice of the adjustment alternating current voltage V_0 enables the effective value of the alternating current voltage across the said elements to be changed, in a similar manner as described above for the magnetic circuits, by means of voltage pulses of suitable value and direction, to assume a high or a low value. Here again taking the output voltage from L or a winding coupled magnetically thereto is more advantageous for the ratio

$$\frac{V_2}{V_3}$$

than when the output alternating current voltage is taken from one of the elements C and R .

The undesired voltage phenomena which, with the magnetic type, occur in the case of a simple core, also occur with the dielectric type, if this comprises a single capacitor. This may be obviated in a manner known per se similar to that used in the case of the magnetic type. Fig. 8 shows an embodiment of such a push-pull dielectric trigger circuit, G designating a supply generator, V_0 a direct current voltage source, T a signal oscillation voltage source, C_1 and C_2 similar non-linear capacitors, L_1 and L_2 similar inductance coils and S_1 , S_2 and S_3 blocking transformers. The supply generator oscillations are connected to the non-linear elements in push-pull, and the signal oscillation is connected to these elements in co-phase.

The required output voltages may be taken across the pairs of terminals $a-b$, $c-d$ and $e-g$, the voltages across the pairs of terminals $a-b$ and $c-d$ comprising only components the frequencies of which are odd multiples of the supply frequency and the voltages across the pair of terminals $e-g$ comprising only components the frequencies of which are even multiples of the supply frequency.

Trigger circuits of the magnetic or dielectric type as hereinbefore described are capable of replacing other known trigger circuits in many cases.

In some uses the pulse train to which the trigger is required to respond is such that all the pulses are of the same polarity.

It is possible for the trigger circuit arrangement according to the invention to be adapted to this last-named kind of pulse trains by converting such a pulse train in a manner known per se into a pulse train which in its action is equivalent to a pulse train the pulses of which are alternately positive and negative, the conversion being effected by extending the input circuit to become an aperiodically damped resonant circuit the resonant frequency of which should materially exceed the impulse repetition frequency. Such a circuit converts each impulse into an oscillation which at the end of a period is damped and hence consists of two closely adjacent pulses of opposite polarity. In Fig. 9 such pairs of pulses, viz. 1-2 and 3-4 are shown superposed on the adjusting polarization I_0 or V_0 .

Supposing the trigger circuit to be in the condition A, impulse 1 does not act upon V_{eff} , but impulse 2 causes V_{eff} to pass the condition B. Impulse 3 causes a change of V_{eff} from the condition B to the condition A. However, due to the inertia of the circuit, impulse 4, which closely follows impulse 3, is now not capable of interfering with this change. On the other hand, the inertia of the circuit should not be such as to prevent impulse 3 from effecting a change after the action of impulse 2. Hence, the inertia of the circuit arrangement is thus efficiently used.

It has been stated hereinbefore that the value of $\Delta I_1 + \Delta I_2$, which value is a measure of the minimum signal amplitude required to cause a change from one

stable condition to the other, may be adjusted by means of an impedance included in the circuit connecting the supply generator to the said reactances, as is shown for example in Fig. 6.

Fig. 10 shows a circuit in which the value $\Delta I_1 + \Delta I_2$ is controlled in a different manner, in that the oscillation set up across one of the reactances or across an impedance coupled to the said reactances is rectified and then supplied to the variable reactance or in other words feed-back is provided. This circuit, which is substantially equal to the circuit arrangement shown in Fig. 1 and like elements of which are designated correspondingly, comprises a winding T which is closed through a rectifier cell RF and a resistor RT. The voltage fed into T produces a pulsatory direct current in this circuit which may be smoothed, if required, the direct current component I_t of which in the stable condition is equal either to αV_2 or to αV_3 , and the direction of which is determined by RF, α being controllable by means of RT. According to the direction of the flux produced by this direct current the action of I_0 is counteracted or assisted. It is found that, if the direction of the direct flux set up by the circuit T, RF, RT is equal to the direction of the flux set up by I_0 , the value $\Delta I_1 + \Delta I_2$ decreases but that in this event the transitions caused by ΔI_1 and ΔI_2 are retarded relatively to the initial transition speed and that, if the direction of the direct flux set up by the circuit T, RF, RT is opposite to the direction of the flux set up by I_0 , the value $\Delta I_1 + \Delta I_2$ increases, but that in this event the transitions caused by ΔI_1 and ΔI_2 are accelerated relatively to the initial transition speed. This may be appreciated from consideration of Fig. 11. In this figure the curve of Fig. 3 is again shown, I_0 being the adjusting polarization and ΔI_1 and ΔI_2 the minimum impulse amplitude required if no feed-back is used. Assume now that the feed-back current counteracts the adjusting polarization and this adjusting polarization is made I_{00} . If the circuit arrangement is in the condition in which the effective value V_{eff} is equal to V_3 , the direct current $I_t = I_{th}$ produced in the circuit T, RF, RT is comparatively small. In this event the resultant adjusting polarization is I_1 . To effect a transition from V_3 to V_2 the minimum impulse amplitude required is $I_1 - I_{th} = \Delta I_2$ and this may substantially exceed ΔI_2 . However, this transition will also occur more rapidly than if no feed-back is provided, since during the transition from V_3 to V_2 V_{eff} continuously increases, and hence also I_t from I_{th} to I_{th} , a value of I_t to which corresponds that condition in which $V_{eff} = V_2$. The change in I_t acts as it were in support of the transition started by the impulse.

In the condition in which $V_{eff} = V_2$ the resultant adjusting polarization I_2 is equal to $I_{00} - I_{th}$. Transition to the condition in which $V_{eff} = V_3$ now requires an impulse $I_{th} - I_2 = \Delta I_1 > \Delta I_1$. As this transition I_t is decreased by V_{eff} and thus also acts in support of the transition started by the impulse and this in turn results in the transition from one stable condition to the other being accelerated relatively to the transition without negative feed-back.

In addition, when this negative feed-back is provided the ratio

$$\frac{V_2}{V_3}$$

is found to increase. This is due to the fact that at $I = I_0$ in one condition V_{eff} has not yet quite reached the value V_2 due to the curvature in the unstable region, and likewise in the other condition the value V_3 is not yet quite reached. If comparatively V_3 is much smaller than V_2 the said ratio may be materially increased under the influence of a comparatively low decrease in V_3 .

By plotting ΔI_1 and ΔI_2 from I_{00} in the correct direc-

tion and at the correct level, the level being determined by the points

$$\frac{dV_{eff}}{dI} = \infty$$

5 a new curve is found showing V_{eff} as a function of the current passed by the winding W, if negative feed-back is provided. Fig. 12 shows this curve including the part which initially was symmetrical in relation to the V_{eff} axis. In this left hand part the negative feed-back has changed to positive feed-back. As may be seen from the figure, in the case of positive feed-back the sum of the minimum impulse amplitudes $\Delta I_1 + \Delta I_2$ required for the transitions is materially smaller at an adjusting polarization I_{00}' than without providing positive feed-back. In a manner similar to that used in the case of negative feed-back it may be proved that in the case of positive feed-back the transitions are retarded and that the ratio

$$\frac{V_2}{V_3}$$

is decreased. The figure shows in addition a part designated 1.

25 If a high degree of negative feed-back is provided, the curve shown in Fig. 12 assumes the shape shown in Fig. 13. In this figure V_{eff} is again shown as a function of the current passed by the winding W. Adjusting I to the value I_0 indicated in the figure ensures three stable 30 conditions. Assume the circuit arrangement to be in the condition in which $V_{eff} = V_2$, that is to say at point J. If the impulse designated 1 in the figure is superposed on I_0 , V_{eff} leaps from A to a point B and moves to a point C by way of the branch of the characteristic curve 35 associated with point B. This transition is assisted by the feed-back and consequently accelerated. A subsequent impulse of opposite direction designated 2 in the figure causes V_{eff} to pass from C to D by way of the characteristic curve; thence a discontinuous transition is effected to point E. This transition is retarded, since the negative feed-back current which increases with V_{eff} counteracts the impulse 2; hence the final condition is characterized by the point F and not by the point J which would be reached through G and H, unless the impulse 40 45 50 55 60 65 70 75 80 85 90 95 100 105 110 115 120 125 130 135 140 145 150 155 160 165 170 175 180 185 190 195 200 205 210 215 220 225 caused to become operative through a separating transformer S_1 which is included in the circuit comprising C , S_2 a second separating transformer the inductance of the primary winding of which together with the inductance of the winding of S_1 included in the circuit constitutes the reactance of the opposite polarity and one of the secondary windings of which together with a rectifier RF , a capacitor C_1 and a resistor R constitutes the negative feedback circuit, V_0 is a unidirectional voltage source, and T is an impulse voltage source. The required output voltages which are still alternating current voltages may be taken from a further secondary winding of S_2 . The capacitor C_1 through which the negative feed-back voltage is introduced into the circuit also acts as a smoothing capacitor and is preferably arranged to have a large value. The detected voltages may be taken from across R .

Obviously it is also possible to provide feed-back in push-pull trigger circuits as described with reference to Figs. 4, 5 and 8. Fig. 15 shows by way of example such a magnetic trigger circuit and Fig. 16 a dielectric one. In these circuits the even harmonic oscillations are utilized for the feed-back. It will be understood that the odd harmonics may also be used for this purpose, but this is not advisable, since in some cases the push-pull may be upset.

Trigger circuits in accordance with the invention may be used advantageously as impulse renovators and amplifiers for pulsatory signals, the impulse shape, which in most cases has been materially affected during the transmission from transmitter to receiver, which usually shows itself as a decrease in steepness of the pulse flanks, being thus recovered.

To appreciate this a circuit arrangement as shown in Fig. 1 should be considered. In addition, it is assumed that the half-value duration of the transmitted impulses is equal to the duration of the initially emitted impulses and that the decrease in steepness of leading and trailing edges is identical which is usually likely to be approximately the case in practice. Assuming the height of the pulses reaching the amplifier to be h it will be obvious with the aid of Fig. 17 that, if the pulses are superimposed on an adjusting polarization I_1 in a manner such that $I_1 + \frac{1}{2}h = I_0$, the duration a of the initial impulse the shape of which is shown in the figure by a broken line persists in the voltage which at the output is available as a modulated pulse. In this case ΔI_1 is assumed to be equal to ΔI_2 (Fig. 3), since, if actually α_1 is equal to α_2 , as has been assumed, the period of time $t_1' - t_1$ and $t_2' - t_2$ are also identical, where t_1 is the instant at which the original impulse started and t_2 the instant at which it ended, t_1' being the instant at which the impulse reaching the amplifier causes transition from V_2 to V_3 and t_2' the instant at which this impulse causes transition from V_3 to V_2 . If ΔI_1 is not equal to ΔI_2 , a slightly different choice of the adjusting polarization leads to the same result.

Detection of the output signal of a trigger circuit used in this manner thus produces a signal which is amplified and restored in shape but which is retarded relatively to the initial signal by a period of time $t_1' - t_1$.

If h varies in the course of time provision may be made for the relation $I_1 + \frac{1}{2}h_1 = I_0$ to be satisfied by causing I to be decreased by the same amount by which $\frac{1}{2}h$ is increased.

What is claimed is:

1. A trigger circuit comprising a non-linear variable first reactance, a second reactance of opposite polarity coupled to said first reactance, a source of local oscillations, means connected to supply said local oscillations to said reactances, said first reactance being polarizable in stable and unstable regions, means connected to polarize said first reactance into an unstable region wherein the oscillation in said reactances may assume any one of a plurality of different magnitudes, a source of signal oscil-

lations having a frequency which is low as compared with the frequency of said local oscillations, and means connecting said signal oscillations to said first reactance, said signal oscillations having a magnitude sufficiently great to shift said polarization momentarily into a stable region of said first reactance whereby the oscillation in said reactances is shifted from one to another of said different magnitudes.

2. A trigger circuit, as set forth in claim 1, wherein said first reactance comprises magnetic material.

3. A trigger circuit, as set forth in claim 1, wherein said first reactance comprises dielectric material.

4. A trigger circuit, as set forth in claim 1, further including an impedance connecting said local oscillation source to said reactances, means for adjusting the value of said impedance to cause adjustment of the minimum signal oscillation amplitude at which said shifting of the oscillation occurs.

5. A trigger circuit comprising a non-linear variable first reactance, a second reactance of opposite polarity coupled to said first reactance, a source of local oscillations, means connected to supply said local oscillations to said reactances, said first reactance being polarizable in stable and unstable regions, polarization means connected to polarize said first reactance into an unstable region wherein the oscillation in said reactances may assume any one of a plurality of different magnitudes, a source of pulsatory signal oscillations having a pulse repetition rate which is low as compared with the frequency of said local oscillations, means connecting said signal oscillations to said first reactance, said signal oscillations having a magnitude sufficiently great to shift said polarization momentarily into a stable region of said first reactance whereby the oscillation in said reactance is shifted from one to another of said different magnitudes, rectifying means connected to rectify the oscillations across one of said reactances and produce rectified oscillations therefrom, and means connected to supply said rectified oscillations to said first reactance.

6. A trigger circuit as claimed in claim 5, including means connected to adjust the magnitude of said rectified oscillations to a value whereby said circuit is capable of respectively assuming three different stable regions at different values of polarization produced by said polarization means.

7. A trigger circuit as claimed in claim 5, in which said first reactance comprises two sections connected in push-pull with respect to said local oscillations and connected in co-phase with respect to said signal oscillations.

8. A trigger circuit comprising a variable reactance having a medium which is operable in a non-linear part of its polarization characteristic curve, means connected to polarize said medium in said non-linear part, said reactance being constituted by an inductor having a ferromagnetic core, a source of pulsatory oscillations, a coil magnetically coupled to said ferromagnetic core and connected to said source for supplying pulsatory oscillations to said reactance, a source of local oscillation, said local oscillation having a frequency which is high as compared with the rate of said pulsatory oscillations, a capacitor and a load resistor, said source, said capacitor and said resistor being serially connected across said reactance.

9. A trigger circuit comprising a variable reactance having a medium which is operable in a non-linear part of its polarization characteristic curve, said reactance being constituted by an inductor including a first coil having a first ferromagnetic core and a second coil having a second ferromagnetic core, said coils being connected in series opposition, a third coil magnetically coupled to said first coil, a fourth coil magnetically coupled to said second coil, said third and fourth coils being connected in series aiding a source of pulsatory

oscillations connected across said third and fourth coils for supplying pulsatory oscillations to said reactance, a source of local oscillation, said local oscillation having a frequency which is high as compared with the rate of said pulsatory oscillations, a capacitor and a load resistor, said local oscillation source, said capacitor and said resistor being serially connected across said first and second coils.

10. A trigger circuit comprising a variable reactance having a medium which is operable in a non-linear part of its polarization characteristic curve, said reactance being constituted by an inductor including a first coil, a second coil serially connected to said first coil and a three-legged ferromagnetic core having two outer legs and a central leg, said first coil being wound around one of said outer legs and said second coil being wound around the other of said two outer legs, a third coil wound around said central leg, a source of pulsatory oscillations connected to said third coil for supplying pulsatory oscillations to said reactance, a source of local oscillation, said local oscillation having a frequency which is high as compared with the rate of said pulsatory oscillations, a capacitor and a load resistor, said local oscillation source, said capacitor and said resistor being serially connected across said first and second coils.

11. A trigger circuit comprising a variable reactance having a medium which is operable in a non-linear part of its polarization characteristic curve, said reactance being constituted by an inductor having a ferromagnetic core, a coil magnetically coupled to said ferromagnetic core, a source of pulsatory oscillations connected to said coil for supplying pulsatory oscillations to said reactance, a capacitor connected across said inductor, a source of local oscillation, said local oscillation having a frequency which is high as compared with the rate of said pulsatory oscillations, and an impedance connected in series with said local oscillation source, said impedance and said local oscillation source being connected across said capacitor.

12. A trigger circuit comprising a variable reactance having a medium which is operable in a non-linear part of its polarization characteristic curve, said reactance being constituted by a capacitor containing a dielectric material, means for supplying pulsatory oscillations to said reactance, a source of local oscillations, said local oscillations having a frequency which is high as compared with the rate of said pulsatory oscillations, an inductance and a load resistor, said source, said inductance and said resistor being serially connected across said reactance.

13. A trigger circuit comprising a pair of variable reactances each having a medium which is operable in a non-linear part of its polarization characteristic curve, each of said reactances being constituted by a capacitor containing a dielectric material, a first transformer having a primary winding and a secondary winding having a tap thereon, a second transformer having a primary winding having a tap thereon and a secondary winding, one end of the secondary winding of said first transformer being connected to one end of the primary winding of said second transformer through one of said reactances, the other end of the secondary winding of said first transformer being connected to the other end of the primary winding of said second transformer through the other of said pair of reactances, a direct current source, a signal oscillation source, a third transformer having a primary winding and a secondary winding, said sources and the primary winding of said third transformer being serially connected between said taps, and a source of local oscillation connected across the primary winding of said first transformer, said local oscillation having a frequency which is high as compared with the frequency of said signal oscillation, whereby the secondary winding of said second transformer has an

output voltage comprising only components the frequencies of which are odd multiples of the frequency of the local oscillation and the secondary winding of said third transformer has an output voltage comprising only components the frequencies of which are even multiples of the frequency of the local oscillations.

14. A trigger circuit comprising a variable reactance having a medium which is operable in a non-linear part of its polarization characteristic curve, said reactance being constituted by an inductor having a ferromagnetic core, a first coil magnetically coupled to said ferromagnetic core, a source of pulsatory oscillations connected to said first coil for supplying pulsatory oscillations to said reactance, a second coil magnetically coupled to said ferromagnetic core, a rectifier and a variable resistor connected in series across said second coil, an impedance connected across said inductor, a source of local oscillation, said local oscillation having a frequency which is high as compared with the rate of the pulsatory oscillations, a capacitor and a load resistor, said local oscillation source, said capacitor and said load resistor being serially connected across said inductor.

15. A trigger circuit comprising a variable reactance having a medium which is operable in a non-linear part of its polarization characteristic curve, said reactance being constituted by a capacitor containing a dielectric material, a first transformer having a primary winding and a secondary winding, a second transformer having a first winding, a second winding and a third winding for providing an output voltage, a coupling capacitor, a signal oscillation source, a direct current source, said variable reactance, said coupling capacitor, said first winding and said sources being serially connected across the secondary winding of said first transformer, a source of local oscillation connected across the primary winding of said first transformer, said local oscillation having a frequency which is high as compared with the frequency of said signal oscillations, a resistor connected across said coupling capacitor, and a rectifier connected in series with said second winding across said resistor.

16. A trigger circuit comprising a variable reactance having a medium which is operable in a non-linear part of its polarization characteristic curve, said reactance being constituted by an inductor including a first coil, a second coil serially connected to said first coil and a three-legged ferro-magnetic core having two outer legs and a central leg, said first coil being wound around one of said outer legs and said second coil being wound around the other of said two outer legs, a third coil wound around said central leg, a source of pulsatory oscillations connected to said third coil for supplying pulsatory oscillations to said reactance, a source of local oscillation, said local oscillation having a frequency which is high as compared with the rate of said pulsatory oscillations, a capacitor, a first resistor, said local oscillation source, said capacitor and said resistor being serially connected across said reactance, a fourth coil wound around the central limb of said core, and a rectifier and a second resistor serially connected to said rectifier across said fourth coil.

17. A trigger circuit comprising a pair of variable reactances each having a medium which is operable in a non-linear part of its polarization characteristic curve, each of said reactances being constituted by a capacitor containing a dielectric material, a first transformer having a primary winding and a secondary winding having a tap thereon, a second transformer having a primary winding having a tap thereon and a secondary winding, one end of the secondary winding of said first transformer being connected to one end of the primary winding of said second transformer through one of said reactances, the other end of the secondary winding of said first transformer being connected to the other end of the primary winding of said second transformer through the other of said pair of reactances, a direct current

source, a pulsatory oscillation source, a coupling capacitor, a third transformer having a first winding, a second winding and a third winding, said sources, said coupling capacitor and said first winding being serially connected between said taps, a source of local oscillation connected across the primary winding of said first transformer, said local oscillation having a frequency which is high as compared with the frequency of said pulsatory oscillations, a resistor connected across said coupling capacitor, and a rectifier connected serially with the second winding of said third transformer across said resistor, whereby the secondary winding of said second trans-
